UNITED STATES PATENT OFFICE

108,421

DESIGN FOR A BEVERAGE TUMBLER

Allan Brill, Chicago, Ill.

Application October 28, 1937, Serial No. 72,487

Term of patent 14 years

To all whom it may concern:

Be it known that I, Allan Brill, a citizen of the United States, residing at Chicago, in the county of Cook and State of Illinois, have invented a new, original, and ornamental Design for a Beverage Tumbler, of which the following is a specification, reference being had to the accompanying drawing, forming part thereof.

Figure 1 is a top plan view of a beverage tumbler showing my new design.

Figure 2 is a side elevational view of said beverage tumbler.

Figure 3 is an enlarged view partly in cross section of the upper portion of my tumbler.

The essential feature of the invention resides in a tumbler having adjacent its upper edge two outside, spaced, narrow, convex bulges having a flat narrow intermediate surface, said flat intermediate surface forming a continuation of the wall of the tumbler and positioned in the same plane as the major portion of said wall, as shown in Figure 3, the interior wall thereof, with the exception of the aforesaid bulges which protrude outwardly, presenting a straight line as shown.

I claim:

The ornamental design for a beverage tumbler, as shown and described.

ALLAN BRILL.
